ATTORNEY

UNITED STATES PATENT OFFICE.

ELIAS S. FIEDLER, OF LA CROSSE, WISCONSIN.

PLUMBER'S PLUNGER.

Application filed September 26, 1927. Serial No. 221,966.

This invention relates to plumbing and has special reference to a plumbing plunger of the type used for removing obstructions and clearing drain pipes and the like.

One important object of the invention is to improve the general construction of devices of this character.

A second important object of the invention is to provide a novel form of cup plunger having a compressor plate so arranged as to more effectively collapse the cup than where only a handle is used.

A third important object of the invention is to provide a device of this character with simple and effective means for assembling the parts.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a plunger constructed in accordance with this invention.

Figure 2 is a vertical section therethrough.

Figure 3 is a top plan view thereof.

In the construction of the device here shown there is provided a cup 10 of rubber or the like and while this cup is here illustrated as of substantially hemispherical form it may be made of any shape desired. Extending radially from the center of this cup is a shank 11 having an opening 12 therein for the reception of a handle 13 which thus forms a continuation of the shank.

Thus the shank is relatively rigid when compared with the cup 10. A compressor plate 14 is provided with openings in its center through which the shank extends, the insertion of the handle serving to somewhat expand the shank and cause it to grip the compressor plate firmly. This compressor plate is of such shape that when the handle is pushed down the plate will engage the top of the cup and force down a considerable area of the central part of this cup. The exact shape of the plate may vary somewhat depending on the shape of the cup 10 but in the present instance the compressor

upturned peripheral flange 15 which forms a trough around the plate and is provided with perforations 16 in its bottom. Thus the sharp edge of the plate is prevented from cutting into the rubber while at the same time any water that collects in the trough will drain therefrom. It will be seen from the drawings that the compressor plate is about three quarters the diameter of the cup and while these proportions may vary it will be noted that a considerable area of the cup will be forced down when the handle is depressed.

The device is used in the ordinary way, being placed over the outlet to the drain pipe in a basin, tub or sink and the handle worked up and down.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a device of the kind described, a flexible and elastic cup, a relatively rigid shank extending radially from said cup, a frusto-conical compressor plate having a central opening in which the shank fits and depending from the shank over the central portion of the cup, an upturned flange on the lower edge of said plate, and a handle forming a continuation of said shank.

2. In a device of the kind described, a flexible and elastic cup, a relatively rigid shank extending radially from said cup, a frusto-conical compressor plate having a central opening in which the shank fits and depending from the shank over the central portion of the cup, an upturned flange on the lower edge of said plate, said flange forming a trough around the plate and having spaced perforations in the bottom thereof, and a handle forming a continuation of said shank.

3. In a device of the kind described, a flexible and elastic cup, a relatively rigid shank extending radially from said cup, a frusto-conical compressor plate having a central opening in which the shank fits and

depending from the shank over the central portion of the cup, an upturned flange on the lower edge of said plate, said flange forming a trough around the plate and having spaced perforations in the bottom thereof, said shank having a recess extending inwardly from its end beyond the point of

engagement of the plate on the shank, and a handle having one end fitted in said recess to expand the shank and forcibly engage the shank and plate at the opening in the latter. ¹⁰

In testimony whereof I affix my signature.

ELIAS S. FIEDLER.
